UNITED STATES PATENT OFFICE.

ULYSSES G. McQUEEN, OF NEW YORK, N. Y.

HANGER.

1,322,918.

Specification of Letters Patent. Patented Nov. 25, 1919.

Application filed April 24, 1917. Serial No. 164,203.

To all whom it may concern:

Be it known that I, ULYSSES G. McQUEEN, citizen of the United States, and a resident of New York, in the county of New York 5 and State of New York, have invented certain new and useful Improvements in Hangers, of which the following is a specification.

This invention relates to door hangers and particularly to that class employed for 10 the purpose of operatively supporting horizontally sliding doors.

An object of the invention is to provide a door hanger which can be easily installed and quickly adjusted; one which will include 15 a track and a sliding bar supported therefrom and adapted to move lengthwise of the track and which will have combined and associated therewith a means for preventing the sliding bar from moving vertically out of an intended normal position 20 and also serving to prevent an application of undue strains upon the rail.

Another object of the invention is to provide 25 a door hanger in which means are employed for facilitating an attachment of the hanging brackets or straps thereto to which the door is adapted to be connected.

A still further object of the invention is to 30 provide a construction wherein the sliding door carrier bar or rail is supported from the track by a three-point suspension, the same comprising opposed sets of antifriction bearings disposed between the respective sides of the bar and the sides of the track 35 and a third set of antifriction bearings disposed between the base of the bar and bottom of the track, the said sets of bearings co-operating to sustain and equalize the strain of the weight of the door upon the 40 portions of the track, as well as to secure other desirable advantages hereinafter fully described.

With the above and other objects in view 45 which will appear as the nature of the invention is better understood, the same consists in the improved construction and novel arrangements of parts which will hereinafter be fully described and particularly pointed out in the claims.

In the accompanying drawings, has been 50 illustrated, a single and preferred form of the invention, it being, however, understood that no limitations are necessarily made to the precise structural details therein exhibited, but that changes, alterations and modi-

fications within the scope of the claims may be resorted to when desired.

In the drawings:—

The figure is a vertical section through 60 the hanger.

On reference to the drawing, the hanger includes a track 1, provided with substantially parallel sides 2 and 3, a connecting upper flange 4, and a base flange 4^a. The side wall 2, is provided with a race-way 5, 65 having relatively diverging or angular surfaces 6—6, which are disposed directly opposite similar surfaces 7—7, which are formed in one side of a sliding bar 8. The said surfaces 7—7, constitute a race-way 70 which is adapted to mate with the race-way 5, as clearly shown.

The opposite side wall 3, is provided with a race-way 9, having angularly disposed or relatively diverging surfaces 75 10—10, which mate with similar surfaces 11—11, formed in the other side face of the sliding bar. Each of the last mentioned surfaces combine with one another to form a race-way 12, in the bar, which is located 80 directly opposite the race-way 9.

The base flange 4^a, is also provided with a race-way 13, having angularly disposed or relatively diverging surfaces 14—14, while at the base of the bar 8, is formed a 85 race-way 15, having angularly disposed or relatively diverging surfaces 16—16.

In all of the mentioned race-ways are 90 spherical anti-friction bodies 17, which are mounted in openings formed in a spacer 18, which is interposed between the sliding bar and the track 1, and is designed to hold said spherical bodies equi-distantly spaced apart with a consequent equal distribution of the load against said body.

The relatively diverging surfaces formed 95 in the respective race-ways both in the track 1, and in the sliding bar 8, extend at a tangent to the anti-friction bodies so as to minimize the contact between the bodies and 100 said surfaces which will permit the bar 8, to slide with great ease in the length of the track and also enable the door to be adjusted with but little exertion on part of the operator.

The tangential contact of the walls of the race-ways with the anti-friction bodies also furnishes a means whereby the sliding bar is positively held against any irregular or 110 undue vertical movements when the door is

adjusted. The anti-friction bodies at the base of the bar 8, serve to proportionately receive certain axial strains which are applied to the structure when the door is moved in one direction or another and incident to this arrangement, I positively prevent any tendency of the load from forcing the anti-friction bodies in the vertical sides of the bar 8, in the direction of the restricted portions of the race-ways 5 and 9. This construction also operates to prevent the sides 2 and 3, from separating laterally under the action of weight when supported from the bar 8.

15 A strap or bracket 19, is employed for the purpose of connecting the bar 8, with the door and as shown, it is provided with a continuous lug 20, which fits a corresponding groove 21, in the bar 8. Said portion 20 of the bracket is permanently secured to the bar 8, by means of rivets or equivalent fastenings 22. The base of the bracket is extended in a lateral direction beneath the track 1, where it may be connected with the door by means of the usual adjustment screws 23. The upper end of the track 1, is provided with bolts 24, which are adapted to be adjusted laterally in correspondingly formed slots 25, in a supporting 30 rail 26.

An essential feature of my invention consists in the construction of the channelled track 1 with the bottom wall 4^a and provision of the lower set of antifriction bearings 17 between the same and the base of the sliding bar 8. By this means a three-point suspension for the door is provided comprising the two upper sets of side bearings 17 and the bottom set of bearings 17. One advantage gained by this construction is that the strain of the weight of the door is partly removed from the upper side bearings 17 and a certain proportion of the weight transferred to the bottom bearings 17, thus 45 supporting the door so as to mutually and uniformly impose the strain on all three suspension points. By thus relieving the side bearings from the total dead weight of the door and imposing upon them only a portion of the weight, it will be obvious that outward thrust pressure of the side bearings upon the walls 2 and 3, caused by the down pull of the door, is entirely avoided, and spreading of such walls under such pressure 50 thereby prevented. Hence the use of clips or other braces to reinforce the side walls may be dispensed with and the track may be made of thinner metal and of restricted width without sacrificing structural 60 strength. As, also, the strain is mutually sustained by the three sets of bearings, there is a reduction of frictional pressure and consequently greater ease of motion of the bar 8 is obtained. As shown, the bottom bearings 65 17 are preferably in a vertical plane parallel

with and equidistantly between the vertical planes of the side bearings, while the latter are disposed in transverse alinement above the horizontal center of the bar 8. The effect of this arrangement is to better dispose 70 the bearing surfaces to stably support the bar 8 and to establish counteracting resistances at the several bearing points against the tilting of the bar either vertically or laterally.

Another advantage gained by my improved construction and arrangement of the bearing surface is that, owing to the removal of overstrain from the side walls 2 and 3 and the additional support afforded by the bottom bearing, the track may be made of thinner metal than is possible with the use of the side bearings alone. The cost of manufacture may thus be reduced without sacrificing strength, the increased stability given 80 by the bottom bearing in fact rather more than compensating for any theoretical loss of strength from the use of thinner metal. The use of comparatively thin metal also allows the track to be made of narrow width 85 to suit thin doors, which, as the use of clips or other braces adding width may also be dispensed with, permits of the mounting of two thin sliding doors in close relation to avoid the presence of an unsightly gap between them and the use of abrasion strips or the like upon the doors to conceal such gap. Doors of restricted thickness may 90 therefore be hung in a compact and highly finished manner, as will be readily understood.

What is claimed as new is;

1. In a door hanger, a track having side walls and a bottom wall, a hanger bar between said side walls and above said bottom wall, said hanger bar and said track being slidably movable with respect to each other, the opposing lateral faces of the bar and side walls being provided with coacting grooves forming supporting surfaces and raceways, sets of antifriction bearing members engaging said raceways between the said opposing lateral faces of the side walls and hanger bar and supporting the bar from said side walls, and a set of antifriction bearing members interposed between the base of the hanger bar and the bottom wall and additionally supporting the bar from said bottom wall.

2. In a door hanger, a track having side walls and a bottom wall, a hanger bar between said side walls and above said bottom wall, said hanger bar and said track being slidably movable with respect to each other, the said bar and side walls having parallel vertical faces provided with coacting grooves forming supporting surfaces and raceways arranged in transverse alinement above the horizontal center of the bar, and the opposing faces of the bar and bottom

wall being provided with co-acting grooves forming a raceway disposed in a vertical plane on a line between the first named raceways, sets of antifriction bearing members disposed in said raceways between the said opposing faces of the side walls and hanger bar and supporting the bar from said side walls, and a set of antifriction bearing members disposed in said raceway between the 5 bar and bottom wall and additionally supporting the bar from the bottom wall.

3. In a door hanger, a channeled track having side walls, one of said side walls depending below the other and provided with 10 a flange disposed on a line between said side walls, a hanger bar mounted between the side walls and above the bottom wall, said hanger

bar and said track being slidably movable with respect to each other, the bar and side walls having opposed vertical faces provided 20 with grooves forming supporting surfaces and raceways and the opposing surfaces of the bar and bottom wall being provided with grooves forming a raceway disposed on a vertical line between the first named raceways, sets of antifriction bearing members disposed in the raceways between the opposing faces of the hanger bar and the side walls and supporting the said bar from said side walls, and a set of antifriction bearing 25 members disposed in the raceway between the bar and the bottom wall and additionally supporting the bar from the bottom wall.

ULYSSES G. McQUEEN.
